Primary Examiner — Celia Murphy*Assistant Examiner* — Clare Ann Gannon*(74) Attorney, Agent, or Firm* — Lucas & Mercanti, LLP(57) **CLAIM**

The ornamental design for a shoe, as shown and described.

DESCRIPTION

FIG. 1 is a front perspective view of the shoe according to the design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines on the surface of the shoe and periphery represent stitching. The broken lines showing the shoe sole form no part of the claimed design.

1 Claim, 7 Drawing Sheets(56)
